TOOTHPASTE HOLDER

Rachelle R. Smith, R.D. 2,
Mars, Pa. 16046

Filed Apr. 9, 1971, Ser. No. 132,937

Term of patent 14 years

Int. Cl. D6—06

U.S. Cl. D6—95

FIG. 1 is a front perspective view of toothpaste tube holder showing my new design.

FIG. 2 is a side elevational view thereof.

FIG. 3 is a top plan view thereof.

FIG. 4 is a bottom plan view thereof.

What I claim:

The ornamental design for a toothpaste holder, substantially as shown.
